UNITED STATES PATENT OFFICE.

JOHN H. B. BRYAN, OF BUFFALO, NEW YORK.

APPARATUS FOR DRAWING PATTERNS FROM MOLDS.

SPECIFICATION forming part of Letters Patent No. 658,973, dated October 2, 1900.

Application filed November 28, 1899. Serial No. 738,549. (No model.)

To all whom it may concern:

Be it known that I, JOHN H. B. BRYAN, a citizen of the United States, residing at Buffalo, in the county of Erie and State of New York, have invented new and useful Improvements in Apparatus for Drawing Patterns from Molds, of which the following is a specification.

This invention relates to an apparatus for drawing patterns out of sand molds after the latter have been formed in the flasks. Heretofore patterns have been withdrawn by hand from sand molds made in the ordinary manner. In order to enable the pattern to be drawn by hand, it is necessary to loosen the pattern in the mold by rapping. When the pattern is large or deep or has little draft, considerable rapping is necessary to loosen the pattern from the sand, whereby the mold is enlarged to a greater or less extent. In drawing the pattern by hand, especially when the pattern is large or intricate, the mold is liable to be damaged by breaking off pieces here and there and otherwise. These imperfections of the mold have to be repaired by the molder, which requires great skill and care and adds considerably to the cost of the mold and so to the cost of producing the casting.

The object of my invention is the production of an apparatus by which patterns can be drawn from molds with ease and certainty and without danger of damaging the mold, thereby reducing the cost of producing the mold and producing molds which are closely in accord with the patterns.

My improved apparatus consists, essentially, of one or more suction-holders, which are placed upon the pattern and from which the air is exhausted to attach them to the pattern and which are then raised on a guide device to draw the pattern from the mold. The apparatus is provided with various devices whereby these operations are performed with ease and certainty and also with devices for carrying the pattern to the desired place of deposit.

In the accompanying drawings, consisting of three sheets, Figure 1 is a side elevation, partly in section, of one form of my pattern-lifting apparatus. Fig. 2 is a top plan view of the same. Fig. 3 is a horizontal section in line 3 3, Fig. 1. Fig. 4 is a vertical longitu-

dinal section, on an enlarged scale, of the pattern-holders and adjacent parts. Fig. 5 is a fragmentary vertical section, on an enlarged scale, of the air-valve. Fig. 6 is a similar section of the air-valve, taken at right angles to Fig. 5. Figs. 7 and 8 are fragmentary transverse sections in lines 7 7 and 8 8, Fig. 4, respectively. Fig. 9 is a fragmentary horizontal section in line 9 9, Fig. 4. Fig. 10 is a fragmentary side elevation, partly in section, of a modification of my pattern-lifting apparatus. Fig. 11 is a fragmentary longitudinal section, on an enlarged scale, of the pattern-holder and adjacent parts viewed in the same direction as Fig. 10. Fig. 12 is a fragmentary transverse section in line 12 12, Fig. 11. Fig. 13 is a vertical section of the air-valve which controls the vertical movement of the pattern-holder in the modified construction. Fig. 14 is a similar section of this air-valve, taken at right angles to Fig. 13.

Like letters of reference refer to like parts in the several figures.

Referring to Figs. 1 to 9, A represents the molding-bench, upon which the molding-flask a is placed in the usual manner for molding the pattern in the sand.

B represents a horizontally-movable frame, which is arranged above the molding-bench and which consists, essentially, of an upright shaft b, provided with an upper arm b', an intermediate arm b², and a lower arm b³, which project horizontally forward from the shaft, and an upright brace-bar b⁴, connecting the outer ends of the intermediate and lower arms. The upper arm b' is preferably bent and formed in one piece with the shaft, while the intermediate and lower arms are made separate and fastened to said shaft. The upright shaft is journaled in bearings c c', so as to be capable of rocking horizontally. These bearings are secured to a wall, post, or other stationary support C in rear of the molding-bench.

D represents an upright hollow lifting-rod, which is capable of sliding vertically in guides d d', arranged at the outer ends of the intermediate and lower arms b² b³. This rod is raised and lowered by means of a bifurcated lever E, which is pivotally connected to the lifting-rod and pivoted loosely at its rear end to the rock-shaft b by a transverse pin e, se-

cured to the shaft and passing through longitudinal slots in the bifurcations of the lever. The front end of the lever is preferably widened to form a handle e' . The weight of the hollow lifting-rod and the parts connected therewith is balanced by a weighted arm F , pivoted at its rear end on the shaft of the rocking frame and connected at its front end with the lifting-rod by a chain or other flexible connection f , which passes over a guide-wheel f' on the upper arm of the rocking frame.

G represents a three-way cock arranged at the upper end of the hollow lifting-rod for either connecting the interior of the hollow rod with the exhaust mechanism or breaking the vacuum in the rod by opening a communication between the interior of the rod and the external atmosphere. This cock has a lower branch or nipple g , which connects with the hollow lifting-rod, a lateral branch or nipple g' , connected by a flexible tube g^2 with an air-exhaust device, and an upper branch or nipple g^3 , which opens into the atmosphere. The chain of the balancing-lever can be conveniently connected with the hollow rod through the cock G by an open plug g^4 , which is screwed into the upper nipple g^3 of this cock and provided with an eye, to which the chain is attached, as represented in Figs. 1, 5, and 6. The rotary plug g^5 of the cock is provided with an arm g^6 , which is adapted to engage alternately with upper and lower stops or tappets h h' as the lifting-rod is raised and lowered. These tappets are adjustably secured to an upright supporting-rod H , which depends from the front end of the upper arm of the rocking frame, as shown in Figs. 1, 2, and 6. When the lifting-rod is lowered, the arm of the valve strikes the lower tappet h' and the valve-plug is turned, so as to connect the interior of the rod with the exhaust-tube g^2 , whereby the air is exhausted from the rod. During the last part of the upward movement of the rod the arm of the valve strikes the upper tappet h , whereby the plug of the valve is turned, so as to cut off the interior of the lifting-rod from the exhaust and connect the interior of the rod with the atmosphere, thereby breaking the vacuum in the rod.

I represents two suction cups or holders, which are supported from the lower end of the tubular lifting-rod in such manner that these holders can be placed upon the pattern by lowering the rod and can be raised with the pattern by raising the rod. These suction-holders communicate with the interior of the tubular lifting-rod, so that when these holders have been placed upon the pattern the air can be exhausted from these holders in order to cause the same to attach themselves firmly to the pattern. These holders are attached to a supporting-head J , which is connected with the lower end of the lifting-rod by a flexible coupling K . The latter enables the two holders to tilt with reference to the rod,

if necessary, in seating themselves snugly upon the upper side of the pattern. The details of these parts, as shown in the drawings, are as follows: Each holder consists, preferably, of an upright supporting-stem i , a supporting-disk i' , secured to the lower end of the stem and provided with a depending conical flange i^2 , a conical clamping-ring i^3 , secured to the under side of the disk i' , and a projecting elastic contact-rim i^4 , of rubber or similar material, which is clamped between the disk and the ring. The stem of the suction cup or holder is provided at its upper end with a horizontal supporting-arm i^5 , which is arranged in an opening of the supporting-head J . The supporting-arms of both suction-holders are arranged one upon the other or side by side and are secured by clamping-screws i^6 . Upon loosening these screws the suction-holders can be adjusted toward or from each other, as the size or form of the pattern may require. The lower portion of the stem of each suction-holder is hollow and connected by a flexible tube i^7 with the interior of the hollow coupling K . This coupling consists, preferably, of an upper annular disk or plate k , having a boss on its upper side, which is secured to the lower end of the lifting-rod, a smaller lower annular disk or plate k' , having a nipple on its lower side which is secured by a coupling-stein k^2 to the upper end of the supporting-head J , and a flexible ring or annular plate k^3 , of rubber or other suitable material, arranged between the upper and lower disks and secured with its outer edge to the margin of the upper disk and with its inner edge to the margin of the lower disk.

While the operator is molding the pattern in the flask the rocking frame is turned to one side and the suction-holders are raised to their highest position, in which the exhaust is cut off by the three-way cock from the hollow lifting-rod. After the operator has finished molding the pattern the rocking frame is swung forwardly, so that the suction-holders stand over the pattern. The operator now depresses the hand-lever, whereby the hollow rod and the holding devices are lowered and the cock is turned so as to connect the exhaust with the hollow rod, thereby exhausting the air from the suction-holders and causing the latter to attach themselves firmly to the pattern. The elastic bearing-rim of each holder permits the latter to adjust itself to any slight irregularities in the surface of the pattern; but if a considerable unevenness exists the holding devices tilt, by reason of the yielding coupling K , until both holders engage properly with the pattern. The yielding coupling between the holding device and the lifting-rod is especially useful when lifting large patterns from the flask, in which case the holders are arranged at a considerable distance apart, which renders it difficult to adjust the holders accurately. After the holders are firmly

attached to the pattern the operator raises the lifting-rod, whereby the pattern which is attached to the holders is lifted from the mold in the flask. The last portion of the 5 upward movement of the lifting-rod turns the three-way cock so as to cut off the exhaust from the suction-holders and place the latter in communication with the atmosphere, whereby the vacuum is broken and the pattern is released from the holders. In that case the operator takes hold of the pattern before the suction-holders release the same. The rocking frame carrying the holding devices is then swung to one side to clear the 15 space above the molding-flask and permit the operator to remove the finished mold and prepare the next mold. If the operator desires to carry the pattern to one side before it is released by the holders, he does not raise the 20 rod so high that the suction is cut off, but simply high enough to clear the flask. He then swings the frame and pattern to one side and raises the rod fully when the pattern has reached the desired position.

25 The suction-holders adapt themselves easily to the upper surface of the pattern and attach themselves readily and firmly to the pattern at the points where they come in contact with the pattern without disturbing the latter or the mold in which the pattern is embedded. The pattern is drawn from the mold by a straight upward pull, which does not disturb the mold to any appreciable extent and whereby injury to the mold is avoided, 30 thus doing away with the necessity of completing or repairing the mold by hand after the pattern has been drawn, whereby the cost of molding is greatly reduced, better molds are produced, and the time required for producing a mold is considerably lessened. The rapping of the mold required for detaching the pattern from the sand preparatory to drawing the pattern is inconsiderable and can be conveniently effected by the following device.

45 M represents a two-armed rapping-lever, which is pivoted to the supporting-head J by a pin m , which is secured by a clip m' to the lower side of the supporting-head, as shown in Figs. 1 and 7. Each arm of the rapping-lever is provided with a hammer m^2 , which extends laterally underneath the supporting-arm of the adjacent suction-holder, as shown in Figs. 4, 8, and 9. The rapping-lever is provided on its upper side with a handle m^3 , 50 whereby it may be rocked. After the holders are lowered upon the pattern the rapping-lever is rocked a few times, so that its hammers strike the arms of the holders alternately and vibrate the holders, and through 55 the holders the pattern, thereby causing the latter to be loosened in the molding-sand.

In the modified construction of my apparatus shown in Figs. 10 to 14 only one suction-holder is employed and the raising and lowering is effected pneumatically instead of by hand. In this construction the hollow lift-

ing-rod extends through a vertical cylinder N, which is secured to a horizontal rock-arm n. The lifting-rod is provided with a piston n' within the cylinder. The ends of the cylinder are connected by pipes o with a four-way cock o' , which is connected with a flexible branch o^2 of the exhaust-pipe. This cock is turned by hand and so constructed that when turned in one direction the upper 70 end of the cylinder is placed in communication with the exhaust and the other end of the cylinder is connected with the atmosphere, as shown in Fig. 13, thereby raising the piston and the parts connected therewith, as 75 shown in Fig. 10. Upon reversing the four-way cock the lower end of the cylinder is connected with the exhaust and the upper end with the atmosphere, thereby lowering the piston and the parts connected therewith. 80 85

The single suction-holder I' can be connected directly with the lower end of the hollow lifting-rod by a rigid connection—for instance, a coupling-pipe p—because with a single holder the elastic rim of the holder is 90 usually sufficient to enable the holder to bear evenly on the pattern. In the holder shown in Figs. 10 to 12 the elastic rim q is secured directly to the supporting-disk q'. The rapping-lever M', as shown in Figs. 10 95 to 12, is pivoted on a pin q^2 , extending through the pipe p, and its hammers strike the under sides of arms q^3 , which project from opposite sides of the pipe p.

I claim as my invention—

1. In an apparatus for drawing patterns from molds, the combination with a horizontally-movable supporting-frame having a vertical guide, of a hollow vertical lifting-rod arranged in said guide and capable of vertical movement therein, a suction-head attached to the lower end of said rod and communicating therewith, and a suction-pipe connected with the upper portion of said rod, substantially as set forth.

2. In an apparatus for drawing patterns from molds, the combination with a supporting-frame capable of swinging horizontally about a vertical pivot and having at its free end a vertical guide, of a vertical lifting-rod arranged in said guide and capable of vertical movement therein, a suction-head attached to the lower end of said rod, and a suction-pipe connected with said head, substantially as set forth.

3. In an apparatus for drawing patterns from molds, the combination with a horizontally-movable supporting-frame having a vertical guide, of a vertical lifting-rod arranged in said guide and capable of vertical movement therein, a suction-head attached to the lower end of said rod, a suction-pipe connected with said head, and a counterbalancing device mounted in said frame and connected with said lifting-rod, substantially as set forth.

4. The combination with an upright rod capable of vertical movement, and a suction-

holder arranged below said rod, of a flexible coupling connecting said holder with said rod, substantially as set forth.

5. The combination with a hollow rod adapted to be placed in communication with an exhaust, of a suction-holder, and a flexible coupling connecting said holder with said rod, substantially as set forth.

6. The combination with a hollow rod adapted to be placed in communication with an exhaust, of a flexible coupling communicating with the lower end of said rod, a supporting-head carried by said coupling, a suction-holder, attached to said head, and a flexible pipe connecting said holder with said coupling, substantially as set forth.

7. The combination with an upright rod capable of up-and-down movement, of a suction-holder and a rapping device connected with the lower end of said rod, substantially as set forth.

8. The combination with an upright rod capable of up-and-down movement, of a supporting-head arranged at the lower end of said rod, a suction-holder carried by said head, and a rapping device also carried by said head, substantially as set forth.

9. The combination with an upright rod capable of up-and-down movement, of a suction-holder connected with the lower end of said rod, and a rapping device carried by said rod and adapted to jar said suction-holder, substantially as set forth.

10. The combination with an upright rod capable of up-and-down movement, of a supporting-head connected with the lower end of said rod, a suction-holder attached to said head, and a rapping device also attached to said head and adapted to jar said suction-holder, substantially as set forth.

11. The combination with an upright rod capable of up-and-down movement, of a supporting-head connected with the lower end of

said rod, suction-holders provided with arms which are secured to said head, and a rapping device pivoted to said head and adapted to strike said arms, substantially as set forth.

12. The combination with a supporting-frame having a vertical guide, of a vertical, hollow lifting-rod arranged in said guide and capable of vertical movement therein, a suction-head attached to the lower end of said rod, a three-way cock communicating with said rod above said head and provided with an actuating-arm, and stops arranged on said frame, one above the other, and receiving the actuating-arm of said cock between them, substantially as set forth.

13. The combination with a supporting-frame having a vertical guide and capable of vertical movement therein, of a vertical, hollow lifting-rod arranged in said guide and capable of vertical movement therein, a suction-head attached to the lower end of said rod, a three-way cock communicating with said rod above said head and provided with an actuating-arm, a vertical lifting-rod secured to said frame, and stops adjustably secured to said rod, one above the other, and receiving the actuating-arm of said cock between them, substantially as set forth.

14. The combination with a hollow rod capable of up-and-down movement and carrying a suction-holder at its lower end, of a three-way cock at the upper end of said rod, provided with a nipple for connection with an exhaust and with an air-inlet, a hollow plug secured to said inlet, and a counterbalance attached to said plug, substantially as set forth.

Witness my hand this 23d day of November, 1899.

JOHN H. B. BRYAN.
